This invention relates to apparatus for effecting the transfer of data from a data source to a data storage device the operation of which is not synchronised with the data source.

The invention is particularly suitable, for example, in connection with the transfer of data from a magnetic tape to a magnetic drum storage device. Although it is relatively easy to feed the tape at approximately the correct speed, the starting and stopping of the tape, stretching of the tape and slip between the feeding rollers and the tape make it very difficult to ensure that the data is read from the tape in exact synchronism with the movement of the drum. Furthermore, it is usual for a block of data to be recorded at chosen address locations or positions on the drum, which requires that reading of the block of data on the tape must commence at a predetermined point in the rotation of the drum, if the data is transferred directly from the tape to the drum.

In the past, the problems of synchronisation have been avoided by providing a large buffer store between the input source and the main store, that is, between the tape and the storage drum in the example considered. The buffer store is first loaded with one or more blocks of data from the tape in synchronism with the tape movement, and the block or blocks are then transferred to the drum in synchronism with the movement of the drum. The buffer store is designed to accept a relatively large amount of data, for example, that recorded in one complete track of the drum. The buffer store is therefore likely to be a complex and costly item of equipment.

It is an object of the invention to provide an improved data transfer arrangement using a relatively small intermediate store between the data source and the main storage device.

It is a further object to provide a data transfer arrangement in which the data source and the main storage device may be out of synchronism by an amount corresponding to a predetermined number of data signals and in which the data transfer is effected through an intermediate store with a storage capacity less than such predetermined number of data signals.

According to the invention apparatus for recording serially occurring data signals from a data input source in a series of sequentially available data storage locations forming a track of a main magnetic data store, includes means for generating input timing pulses synchronised with the said data signals, means for generating output timing pulses synchronised with the sequential availability of said storage locations in the main store, an intermediate data store providing a plurality of settable data signal storage positions, a first switching device adapted to be controlled by both the input and output timing pulses and to select which storage position of the intermediate store is to be set in accordance with each data input signal at least two magnetic recording heads spaced apart along said track of the main store, and means adapted to read out serially to a second switching device the signals stored in the intermediate store, the second switching device being adapted to select the recording head to which each signal read out from the intermediate store is fed in accordance with the difference between the number of input timing pulses and output timing pulses which are generated, whereby the data

2

input signals are recorded in successive ones of said series of storage locations independently of variation within predetermined limits of the time of occurrence of said input signals in relation to the availability of said storage locations.

The invention will now be described, by way of example, with reference to the accompanying drawings, in which:

FIG. 1 is a block schematic diagram of an arrangement for transferring data from a magnetic tape to a magnetic drum store; and

FIG. 2 is a block schematic diagram of a modification of FIGURE 1.

A magnetic tape 1 (FIGURE 1) carries a data recording track 2. The tape can be fed past a magnetic reading head 3, so that the head senses signals recorded in the track 2. The feeding mechanism is indicated schematically by a feed roller 4, which can be driven through a friction clutch 5 by a motor 6.

The signals induced in the winding of the head 3 are fed to an amplifier 7. The amplifier provides a source of data output signals on a line 8 and a clock pulse corresponding to each data signal, on a line 9. The data in the track 2 may be recorded in binary, binary coded decimal or other desired form, but it is assumed that each data signal is positively recorded. For example, positive and negative magnetic saturation of the tape may be used to record a binary one and a binary zero, respectively. This enables a clock pulse train to be derived from the data signals, a clock pulse occurring for each data signal whether it is a one or a zero.

It is necessary that input clock pulse signals synchronised with the data source signals shall be available, but a separate clock pulse track on the tape and an associated reading head may provide the clock signals, instead of the clock signals being derived from the data signals. Alternatively, a double track recording may be used, in which the signals representing one are recorded in one track and zero signals are recorded in the other track and clock signals are produced by combining signals from both tracks.

The data read from the tape is recorded in a data track 10 of a main storage device in the form of a magnetic drum 11. The drum is continuously rotated by a motor 12. The drum also has an output clock pulse track 13, which is read by a magnetic head 14. It will be assumed that the drum is driven at such a speed that the average frequencies of the clock pulses from the tape and the drum are approximately the same. For example, the motors 6 and 12 may be synchronous motors driven from a common power supply. However, the movement of the tape and the drum are not mechanically synchronised in any way. Any changes in the relative speeds of the tape and the drum occur slowly relative to the frequency of the data signals and clock pulse trains, owing to the inertia of the driving arrangements.

The data is transferred from the tape to the drum through an intermediate store 15, which consists, in the present example, of a shifting register with five stages 15/1 to 15/5. Each data is entered into the register by means of one of five gates 16/1 to 16/5 which are controlled by the individual stages 17/1 to 17/5 of a ring counter 17. The state of the ring counter determines which of the gates 16 is operative to pass a data signal. Each stage of the register may consist of a conventional bi-stable flip-flop. Each stage of the register may be set by a data signal passed by the corresponding one of the gate 16, and each stage except the stage 15/5 may be set by the preceding stage in normal shift register fashion.

The data signal output line 8 is connected to the input of two gates 18 and 19. These two gates are controlled by the voltages at the two anodes of a conventional mono-

stable flip-flop 20. The flip-flop is normally in the off state and the anode voltages are then such that the gate 18 passes the data signals on the line 8 and the gate 19 does not. The flip-flop is switched to the on state each time a clock pulse from the drum is applied to it from the head 14, via amplifier 21. The anode voltages are then such that the operative conditions of the gates 18 and 19 are interchanged. The output of the gate 18 is connected directly to the inputs of the gates 16/1 to 16/5. The output of the gate 19 is connected to the inputs of the gates 16/1 to 16/5 through a pulse delay circuit 22. The gates 18 and 19 prevent interference between data being read into and out of the register 15. The way in which this is achieved will be made clear in explaining the overall operation of data transfer.

The counter 17 is a conventional form of reversible ring counter with separate add and subtract inputs. Clock pulses from the tape are applied to one input over line 9. Clock pulses from the drum are applied by amplifier 21 to the other input. Each stage of the counter controls the corresponding one of the gates 16/1 to 16/5. A gate 16 is open only when the corresponding stage of the counter is in the on state, and only one stage of the counter is on at any particular time.

It will first be assumed, for the purpose of explanation of the circuit operation, that the drum and tape are running at the same speed and that the relative timing of the drum and the tape is such that a drum clock pulse occurs between each pair of clock pulses from the tape. Furthermore, it will be assumed that the stage 17/1 of the counter 17 is on and that the flip-flop 20 is off. When the first data signal is read from the tape by the head 3, the signal will be fed through the amplifier 7, line 8, gate 18 and gate 16/1 to set the stage 15/1 of the register 15 to the on or off state according to whether the signal represented a one or a zero, respectively. The stage 15/1 will be initially off, representing zero, under the postulated conditions, so that only one signal would be effective to switch the stage.

A clock pulse will be produced on line 9 by the reading of the data signal. Assuming that this line is connected to the add input of the counter 17, this pulse will add one, so that the stage 17/1 switches off and the stage 17/2 is switched on. There is an inherent delay in the switching of the counter stages and this allows the data signal to pass through the gate 16/1 before the stage 17/1 switches off and makes the gate 16/1 inoperative.

The voltage of one anode of the flip-flop forming the stage 15/1 of the register controls a gate 23, which also receives drum clock pulses from the amplifier 21. The output of the gate 23 is connected to the input of three gates 24/1 to 24/3. Each of these three gates is controlled by a corresponding one of the stages 25/1 to 25/3 of a ring counter 25, in the same way as the gates 16 are controlled by the counter 17. The outputs of the gates 24/1 to 24/3 are connected to recording heads 26, 27 and 28, respectively.

The heads 26, 27 and 28 are spaced apart along the data track 10 of the drum 11. Each of these heads is spaced apart from the next by a distance equal to that occupied by five consecutive data signal recording positions on the track 10, that is, equal to the number of signals which can be held in the intermediate storage register 15.

One data signal from the tape has been stored in the intermediate storage register as represented by the setting of the stage 15/1 of the register. This stored signal is to be recorded in the first available recording position of the track 10 of the drum. These recording positions are defined by the clock track 13. The gate 23 will be operative to pass the next drum clock pulse to occur, if the stage 15/1 is registering one. The output of the gate 23 is fed in common to the inputs of the gates 24. It will be assumed that stage 25/3 of the counter 25 is on, so that the gate 24/3 passes the output of the gate 23 to

the head 28. The head 28 will thus record a one signal in a recording position of track 10 of the drum. Each of the gates 24 preferably takes the form of the gated recording amplifier which is shown and described in British patent specification No. 820,115. The gate 24/3, for example, supplies no current to the recording head 28 when the stage 25/3 is off. When the stage 25/3 is on but no signal is present at the input of the gate 24/3, the gate drives current through the recording head to saturate the magnetic surface of the drum in one direction to represent zero. The application of an input pulse then causes the direction of the recording current to be reversed to magnetically saturate the drum surface in the opposite direction to represent one. Alternatively, each anode of the stage 15/1 may control a gate corresponding to the gate 23. Clock pulses from the drum are applied to both gates, so that one or the other gate passes the clock pulse depending upon the setting of the stage 15/1. The gates 24 receive the output of one of these two gates directly and of the other through an inverter. The gates 24 receive a pulse of one polarity for a zero and of the opposite polarity for a one. Each of the gates 24 includes a conventional recording amplifier to record a one or a zero, by opposite magnetic saturation of the drum surface, according to the polarity of the pulse applied to the particular gate 24.

The drum clock pulse is also fed as a shift pulse to the register 15. The register will be set to register zero by the shift pulse, since the stages 15/2 to 15/5 were not set previously and the zero setting of stage 15/2 will be shifted into stage 15/1, the register shifting from left to right.

The drum clock pulse applied to the subtract input of the counter 17 will subtract one to switch the stage 17/2 off and to switch the stage 17/1 on. This returns the counter to the original setting.

The drum clock pulse will also switch on the flip-flop 20. The time constant of the flip-flop is such that it reverts to the off state after a time equal to the time required to shift the contents of the register 15. The gate 18 is closed and the gate 19 is opened for this time by the flip-flop, but, since the next data signal is not yet being read from the tape, no signal is passed by the gate 19.

After the flip-flop 20 has switched back the circuit is in the same condition as it was before the first signal was read from the tape. The next signal read from the tape will therefore be stored on stage 15/1 of the register and will then be read out by the next drum clock pulse and recorded in the track 10 of the drum, in the same manner as for the first signal. Subsequent signals read from the tape will be transferred to the drum in a similar manner, so long as the postulated conditions hold.

Now suppose that the tape begins to move faster relative to the drum. The time between the entry into and readout from the stage 15/1 will begin to increase, until a signal is being read from the tape at the same time as the previously read signal is being read out from the register stage 15/1. The flip-flop 20 will have been switched on by a drum clock pulse under these conditions and the gate 18 will be shut. However, the signal on the line 8 is passed by the gate 19, which is now open, to the delay circuit 22. The time delay provided by this circuit is sufficient to allow shifting of the register before the signal reaches the output of the delay circuit and is applied to the gates 16.

The subtract input of the counter 17 is provided with a pulse lengthening circuit, so that a pulse on this input overrides a pulse applied simultaneously on the add input. Thus the counter stage 17/1 is switched on, and the register stage 15/1 has been set to zero by the shift pulse, by the time the signal from the gate 19 is fed through the delay circuit 22 to the gates 16. The stage 15/1

will then be set in accordance with this signal from the delay circuit.

The signal from the gate 19 is also fed through another delay circuit 66 and amplifier 67 to the add input of the counter 17. This amplifier provides a delayed pulse, which occurs after the stage 15/1 has been set by the signal from the gate 19, to switch on the stage 17/2 of the counter.

If the next data signal is read from the tape before the next drum clock pulse occurs, the data signal will be passed by the gate 16/2, since the counter stage 17/2 is now on. When the drum clock pulse does occur it will read out the signal stored on stage 15/1 and will then shift the setting of stage 15/2 to stage 15/1, in readiness for reading out by the next occurring drum pulse.

Each time a data signal is read from the tape without the occurrence of a corresponding drum clock pulse the counter 17 will be advanced one stage and the data signal will be read into a higher stage of the register 15 than the preceding data signal. The limit is reached with a five stage register when five such signals have been read. A sixth signal would return the counter to the original state with stage 17/1 on, but the accompanying data signal would then be entered on a stage of the register which was still storing a previously entered signal and data would therefore be lost.

The condition in which the tape starts to run slower than the drum will now be considered and it will be seen that the limit of five signals difference between the tape and the drum does not apply in this case.

Initially, each data signal will be read into and then read out of the stage 15/1 of the register and will be recorded by the head 26, in the manner described earlier, but as the tape slows down at some point a drum clock pulse will occur before a corresponding data signal has been read from the tape. This clock pulse will switch off the counter stage 17/1 and will switch on the counter stage 17/5. This switching of the stage 17/5 by the stage 17/1 also generates a pulse on line 29a, which is connected to the subtract input of the ring counter 25. This pulse on line 29a switches off the stage 25/3 and switches on the stage 25/2, opening the gate 24/2 to feed signals from the gate 23 to the head 27.

The next data signal to be read from the tape will set stage 15/5 of the storage register through the gate 16/5 which is made operative by stage 17/5 being on. Five drum clock pulses are required to shift the setting of stage 15/5 along the register to stage 15/1 and to read out the signal to the gates 24. However, the head 27 is positioned five recording positions in advance of the head 28, so that the signal is applied to the head 27 at the correct time to record in the recording position following that in which the last recorded signal was recorded by the head 28.

The tape clock pulse on the line 9 which occurs with the data signal which sets stage 15/5 will operate the counter 17 and switch stage 17/1 on again. This transition from stage 17/5 to 17/1 generates a pulse on line 29, which is connected to the add input of the counter 25. The stage 25/3 is thus switched on. However, the next drum clock pulse switches the counter 17 again to put stage 17/5 on and a further pulse is produced on the line 29a. This pulse operates counter 25 to switch on stage 25/2 again. The drum clock pulse also shifts the setting of stage 15/5 of the register to stage 15/4, leaving stage 15/5 ready to be set by the next incoming data signal from the tape.

Another drum clock pulse without a corresponding data signal from the tape will switch on stage 17/4 of the counter, so that the incoming signals from the tape will set this stage. Subsequent unaccompanied drum clock pulses will each step the counter 17 by one stage. A further three such pulses will switch on the stage 17/1. One further unaccompanied drum pulse will then switch on stage 17/5. This will produce a pulse on line 29a,

as before, and counter stage 25/1 will be switched on. This will make the head 26 operative for recording in the track 10 of the drum. This head is advanced by ten signal positions in relation to the head 28.

Further unaccompanied drum pulses will cause stepping of the counter 17 in the manner already described. The limit is reached when the stage 17/1 is normally on once again, since a further unaccompanied drum pulse would again cause operation of the counter 25 and the head 28 would be made operative. Thus, the tape may lag in relation to the drum by up to fifteen signals in the case of the embodiment described. The permissible lag may be increased by providing further heads equally spaced apart along the track 10, the number of gates 24 and stages of the counter 25 being increased correspondingly.

It will be seen that the intermediate storage formed by the register 15 needs to have a capacity only equal to the number of consecutive recording positions which separate adjacent heads on the track 10. The selection of the correct position for entry into the intermediate store is controlled by the counter 17, which is driven in one direction for each entry and in the other direction for each readout. The counter 17 and the gates 16 operate as a stepping switch which may be moved forwards or backwards. It will be appreciated that this stepping switch action may be obtained equally well by using known forms of bi-directional commutators and that the counter may be replaced by a five stage reversible shifting register of which only one stage is on.

The counter 25 and the gates 24 act as a stepping switch in a similar manner to select the particular head to be used for recording each signal read out from the intermediate store. It is convenient to drive the counter 25 by carry pulses derived from the counter 17. However, it is necessary only that the counter 25 should be operated when the tape changes from lagging to leading the drum or vice versa and when the tape lags by five signals or a multiple thereof. The leading or lagging relationship of the tape to the drum is indicated by the difference between the number of input clock pulses which have been generated by the tape as compared with the number of output clock pulses generated by the drum. Hence the counter 25 may be driven by any suitable counting arrangement which is operated by the two sets of timing pulses to form the difference and which provides an indication each time the difference is zero modulo five and each time the sign of the difference changes.

An arrangement using an interlaced recording track is described in British patent application No. 34,981/57. The track is divided into sectors and sub-sectors. Each sub-sector is further divided into a number of storage locations. One coded character is recorded in each sector during one revolution of the drum. Each sub-sector of a sector is used for recording one code element of a character. During succeeding revolutions of the drum, recording takes place in different storage locations of each sub-sector.

In applying the invention to such an interlaced arrangement the recording heads such as 26, 27 and 28 are each spaced apart by a distance equal to one sector. There are eight sub-sectors in a sector and only one signal can be recorded in each sub-sector during a particular drum revolution, so that the register 15 needs eight stages.

The provision of heads spaced apart all around the circumference of the drum also allows recording of a block of data to commence at a specified point of the track 10. This may be effected by the arrangement shown in FIGURE 2, which also shows a modified form of intermediate store. Corresponding elements in FIGURES 1 and 2 are given the same references.

The intermediate store consists of three shift registers 30, 31 and 32. If the track 10 is divided up into sectors and sub-sectors in the manner just described, the spacing between adjacent recording heads is equal to eight consecutive signal recording positions, that is, the spacing is

equal to one sector and each of the registers 30, 31 and 32 has eight stages.

The data output signals on the line 8 are fed to the inputs of three gates 33/1 to 33/3. Each gate is controlled by one stage of a ring counter 34. Each stage of the counter also controls one of a group of gates 35/1 to 35/3. The gates 35 are fed in common from the tape clock pulse line 9. The tape clock pulses are also fed to the input of a counter 36. The counter has a counting capacity equal to that of each of the registers 30, 31 and 32.

It will be assumed that the initial setting of the counter 34 is such that the gates 33/1 and 35/1 are open and that the counter 36 is registering zero. This allows data signals from the amplifier 7 to be fed via line 8 and the gate 33/1 to the input of the register 30. The clock pulses on line 9 are fed through the gate 35/1 to act as shift pulses from the register 30, so that each signal applied to the register is entered into the register under control of the associated tape clock pulse and is shifted along the register under control of subsequent tape clock pulses in conventional manner.

The register 30 is fully loaded after eight data signals corresponding to eight code elements to be recorded in one sector of the drum, have been read from the tape 1. At the same time the counter 36 has received eight clock pulses from the line 9 and as a result of the eighth it produces a carry pulse on line 37. This pulse steps on the counter 34. The counter now opens the gates 33/2 and 35/2 and shuts the gates 33/1 and 35/1. Hence, the next eight data signals to be read from the tape will be fed to the register 31.

A further pulse will be produced by the counter 36 on the line 37 to step on the counter 34, at the same time as the eighth data signal is entered into the register 31. The next eight signals will therefore be fed into the register 32. When this register is full the counter 34 receives a further pulse from the counter 36 which will cause it to be switched to the setting to open the gates 33/1 and 35/1. The register 30 will have been emptied by this time, as will now be explained, and is therefore free to accept a further group of data signals from the gate 33/1.

The pulses from the counter 36 are also fed to one input of a bi-stable flip-flop 38 to switch it on. The voltage of one anode of the flip-flop 38 is applied to a gate 39 to hold it open as long as the flip-flop is on. A track 40 on the drum 11 has a recorded signal corresponding to the end of each sector of the data track 10. These signals are sensed by a head 41 which drives an amplifier 42. The end of sector pulses from the amplifier 42 are fed to the input of the gate 39. Consequently, the gate 39 produces an output pulse in response to the first end of sector pulse to occur after the flip-flop 38 has been switched on, that is, after the register 30 has been filled.

The output pulse from the gate 39 is applied to the other input of the flip-flop 38 to switch it off and to one input of a bi-stable flip-flop 43 to switch it on. The voltage of one anode of the flip-flop 43 is applied to a gate 44 to hold it open as long as the flip-flop is on. The gate 44 then allows drum clock pulses to be fed from the output of the amplifier 21 to three gates 45/1 to 45/3. These three gates are controlled by three stages of a ring counter 46.

The counter 46 is set before the start of a data transfer to open the gate 45/3. The output pulse of the gate 39 is fed to the add input of the counter 46, so that the first pulse steps on the counter and the gate 45/1 is opened. This allows drum clock pulses to be applied through the gate 45/1 as shift pulses to the register 30 to read out in succession the data signals stored in that register. The output signals from the last stage of the register are fed to a group of sixteen gates 47/1 to 47/16, of which only five gates are shown. The output of the gates is connected to a corresponding one of sixteen heads 48/1 to 48/16 which are each spaced apart by a distance equal

to a sector along the track 10, it being assumed that the track 10 has sixteen sectors.

The gates 47 are controlled by the individual stages of a sixteen stage ring counter 49. End of sector pulses from the amplifier 42 are fed to the subtract input of the counter 49 and pulses from the gate 39 are fed to the add input. Before a transfer starts, the counter is driven only by the end of sector pulses since the gate 39 is not opened until the register 30 has been filled. These pulses step the counter so that as the last sector of the track 10 reaches a particular head the corresponding gate 47 is opened by the corresponding stage of the counter 49 being switched on. Thus the first stage of the counter is on to open gate 47/1 during the travel of the last sector past the head 48/1. The end of sector pulse occurring as the end of that sector passes the head 48/1 subtracts one from the counter so that the last stage of the counter 49 is switched on to open the gate 47/16. The last sector now passes the head 48/16 and the next end of the sector pulse switches on the next counter stage to open gate 47/15 and so on. Thus, before a data transfer starts, the counter 49 switches the gates 47 sequentially in such a way that the gate 47 which is open is always that one which drives the recording head which is positioned to record in the last sector of the track 10.

When a transfer is to start, because the register 30 has been filled, the add input of the counter 49 receives an end of sector pulse via the gate 39 and the subtract input receives the same pulse direct. The simultaneous pulses on both inputs cancel each other and the counter is not stepped on. If the last sector had just passed the head 48/14, for example, at the time of the pulse from the gate 39 then the gate 47/14 will have been open for one sector and will now remain open for the passage of the next sector, since the counter has not been stepped on. This next sector is the first sector of the track 10, and the head 48/14 will therefore record the signals read out from the register 30 in the first sector of the track.

The register 31 will have been filled from the tape 40 during the recording of the contents of the register 30, if the tape and drum are running at the same effective speed. Hence, the flip-flop 38 will have been switched on during this time by a pulse from the counter 36 and the next end of sector pulse will pass the gate 39 which is opened 45 by the flip-flop 38. This pulse will occur on completion of the recording in the first sector. As before, the pulse from the gate 39 will prevent the counter 49 responding to the end of sector pulse applied to the subtract input. The gate 47/14 will therefore remain open.

The counter 46 will be operated by the pulse from the gate 39 to open the gate 45/2 to apply shift pulses to the register 31. This will effect recording by the head 48/14 of the contents of the register 31. This recording takes place in the second sector since that sector is now 55 passing under the head 48/14.

The pulse generated at the end of the loading of the register 31 operates the counter 34 to open the gates 33/3 and 35/3. This allows the third group of data signals from the tape to be fed to the register 32. This 60 third group of signals will be recorded in the third sector of the track 10 by the head 48/14 in a manner similar to that already described. This process will continue as long as the drum and the tape run at the same speed.

The transfer is terminated by switching off the flip-flop 65 43 by a pulse from a counter 50. This counter has a capacity equal to one more than the number of groups of signals to be transferred and is operated each time the gate 39 produces an output pulse. The counter 50 will thus produce a carry pulse for application to the flip-flop 70 43 on completion of recording in the required number of sectors. The switching off of the flip-flop 43 closes the gate 44 to prevent any further shift pulses being applied to read out from the registers.

If the tape speed is less than that of the drum, a drum 75 end of sector pulse may occur before all the data to be

recorded in that sector has been entered into one of the registers so that the flip-flop 38 has not yet been switched on. Thus the counter 49 receives a pulse on the subtract input only. This will step on the counter to open the gate 47/13, thus providing an effective delay in the same manner as in switching between the heads 26, 27 and 28 of FIGURE 1.

If the tape runs faster than the drum the add input of the counter 49 receives an extra pulse in the following way.

A gate 51, which receives the pulses on line 37, is opened by the flip-flop 38 when it is on. This gate will pass a pulse only if the flip-flop 38 is already on at the time when the pulse occurs, that is, when this pulse occurs before the flip-flop has been reset by a drum end of sector pulse. The pulses passed by the gate 51 are applied to one input of a flip-flop 52 to switch it on.

A gate 53 receives end of sector pulses from the amplifier 42. This gate is opened by the flip-flop 38 when the flip-flop is off. The output of the gate 53 is applied to the other input flip-flop 52 to switch it off. In switching off, the flip-flop produces an output pulse on a line 54 which is connected in common with the output of the gate 39.

Thus, if the tape runs sufficiently fast for two pulses to occur on line 37 without the occurrence of an end of sector pulse, the flip-flop 52 will be switched on via the gate 51. This flip-flop is set only if the drum has lagged behind the input data by one sector. The drum continues to record continuously, but one of the registers 30, 31, 32 is now full, whilst data is being read out of a second of the registers and data is being read into the third of the registers. The flip-flop 52 will remain on as long as the tape continues to lead the drum by more than one sector. Eventually an end of sector pulse will occur when the flip-flop 38 is off, because either the tape has slowed down, or the last character of a block has already been read in to the intermediate store register. The gate 53 is open under these conditions, so that the flip-flop 52 will be switched off and the resultant pulse will have the same effect as if the gate 39 has passed the end of sector pulse. This allows operation for one extra sector to clear the registers 30, 31, 32. The setting of the flip-flop 52 stores an indication that the tape is leading the drum by more than one sector.

It will be apparent that the amount by which the drum can lag behind the tape, once recording has started, is limited in both modifications, by the amount of data which can be held in the intermediate store. On the other hand the drum may lead the tape by any number of revolutions if heads are spaced apart all the way round the track 10. Consequently the tape speed would normally be adjusted so that it is slightly less than that of the drum.

It will be appreciated that the head selection arrangement of FIGURE 2 may be used with the intermediate store of FIGURE 1 if the necessary number of heads are provided for the track 10.

The effect of the counter which controls selections of the heads associated with the track 10 may be summarized in the following way. The initial setting of the counter is such that, if drum sector pulses only are applied to it, the heads are switched in sequence with the operative head always being that one which can record in the first sector. Thus although the whole of the first sector is available for recording during each sector interval, the drum is in effect stationary as far as the different sectors are concerned, that is, successive recording would occur in the same, not successive, sectors. The occurrence of an input to the counter under control of the tape causes a relative phase shift between the drum and the counting cycle, so that the operative head becomes that which can record in the second sector and so on. It will be apparent that if the counter received a pair of pulses each time under control of the tape, then recording would occur in alternate sectors. In a similar

way, any particular sector can be selected at any time by making the appropriate entry into the controlling counter.

If the heads are controlled by the counter in the sequence opposite to that shown, then the drum and tape pulses are applied to the add and subtract inputs, respectively, of the counter. If the tape is always lagging in relation to the drum, the control counter may be simply an adding (or subtracting) counter, which receives the drum sector pulses through a gate which is effective to suppress one sector pulse for each output pulse from the tape counter 17 or 36.

Although a magnetic tape has been used as an example of a data source, it may readily be replaced by a paper tape or a punched card, or the amplifier 7 may receive serial signals directly from a computer. The drum store 11 may be replaced by a disc with the tracks recorded on the flat face.

The main store has been described as a continuously operating cycle store, in the form of a continuously rotating magnetic drum. It is not necessary that the main store should operate in this manner, but merely that it should provide a series of storage locations which are accessible in succession and that clock pulses synchronously as the locations become available. For example, the arrangement shown in FIGURE 1 would operate in a manner similar to that already described if the tracks 10 and 14 were on a magnetic tape instead of a magnetic drum. Similarly, magnetic tape may be used in the arrangement of FIGURE 2 provided that the tape carries a track 40 in which are recorded block marker signals corresponding to the end of sector signals, or that the equivalent of end of sector pulses are provided by a counter operated by the output clock pulses.

When the storage drum 11 forms part of a computer it may be possible to utilise registers which form part of the arithmetic unit of the computer as the intermediate store, since the capacity of the intermediate store is relatively small.

The various circuit elements shown in block form in the drawings are well known per se. For example, suitable gates, amplifiers, flip-flops and ring counters are described in Chapter II of "Description of a Magnetic Drum Calculator," published by Harvard University Press (1952). A suitable shifting register is described on page 104 of "Automatic Digital Calculators" by A. D. and K. H. V. Booth, published by Butterworths (1953).

I claim:

1. A circuit arrangement for transferring data signals from a data input source to a series of sequentially available storage locations of main data storage means comprising, in combination, input timing pulse generating means for generating input timing pulses synchronized with the data signals of said data input source; output timing pulse generating means for generating output timing pulses synchronized with the sequential availability of the storage locations of said main data storage means; intermediate data storage means having a plurality of settable data signal storage positions; input transmitting means for transmitting data signals from said data input source to said intermediate data storage means and for recording transmitted data signals in the said intermediate data storage means; input switching means connected in said input transmitting means and controlled by both input and output timing pulses for selecting which storage position of said intermediate data storage means is to be set in accordance with each data signal of said data input source; output transmitting means for transmitting data signals from said intermediate data storage means to said main data storage means and for recording transmitted data signals in successive storage locations of the said main data storage means; output switching means connected in said output transmitting means and controlled by both input and output timing pulses for selecting a storage location of said main data storage means in

which a data signal stored in said intermediate data storage means is to be stored in accordance with the difference between the number of input timing pulses and the number of output timing pulses so that data signals of said data input source are stored in successive storage locations of said main data storage means independently of variation within predetermined limits of the time of occurrence of said data signals in relation to the availability of said storage locations, said output switching means comprising means for comparing the number of input timing pulses with the number of output timing pulses and for providing an output varying in accordance with the difference between said number of input timing pulses and said number of output timing pulses.

2. A circuit arrangement for transferring data signals from a data input source including a magnetic tape having data signals recorded thereon and from which said data signals are sensed serially to a series of sequentially available storage locations of main data storage means comprising, in combination, input timing pulse generating means for generating input timing pulses from data signals sensed from said magnetic tape; output timing pulse generating means for generating output timing pulses synchronized with the sequential availability of the storage locations of said main data storage means; intermediate data storage means having a plurality of settable data signal storage positions; input transmitting means for transmitting data signals from said data input source to said intermediate data storage means and for recording transmitted data signals in the said intermediate data storage means; input switching means connected in said input transmitting means and controlled by both input and output timing pulses for selecting which storage position of said intermediate data storage means is to be set in accordance with each data signal of said data input source; output transmitting means for transmitting data signals from said intermediate data storage means to said main data storage means and for recording transmitted data signals in successive storage locations of the said main data storage means; output switching means connected in said output transmitting means and controlled by both input and output timing pulses for selecting a storage location of said main data storage means in which a data signal stored in said intermediate data storage means to be stored in accordance with the difference between the number of input timing pulses and the number of output timing pulses so that data signals of said data input source are stored in successive storage locations of said main data storage means independently of variation within predetermined limits of the time of occurrence of said data signals in relation to the availability of said storage locations, said output switching means comprising means for comparing the number of input timing pulses with the number of output timing pulses and for providing an output varying in accordance with the difference between said number of input timing pulses and said number of output timing pulses.

3. A circuit arrangement for transferring data signals from a data input source including a magnetic tape having data signals and timing signals synchronized with said data signals recorded thereon, said data signals being sensed serially from said magnetic tape to a series of sequentially available storage locations of main data storage means comprising, in combination, input timing pulse generating means for generating input timing pulses from timing signals sensed from said magnetic tape; output timing pulse generating means for generating output timing pulses synchronized with the sequential availability of the storage locations of said main data storage means; intermediate data storage means having a plurality of settable data signal storage positions; input transmitting means for transmitting data signals from said data input source to said intermediate data storage means and for recording transmitted data signals in the said intermediate data storage means; input switching means connected in

said input transmitting means and controlled by both input and output timing pulses for selecting which storage position of said intermediate data storage means is to be set in accordance with each data signal of said data input source; output transmitting means for transmitting data signals from said intermediate data storage means to said main data storage means and for recording transmitted data signals in successive storage locations of the said main data storage means; output switching means connected in said output transmitting means and controlled by both input and output timing pulses for selecting a storage location of said main data storage means in which a data signal stored in said intermediate data storage means is to be stored in accordance with the difference between the number of input timing pulses and the number of output timing pulses so that data signals of said data input source are stored in successive storage locations of said main data storage means independently of variation within predetermined limits of the time of occurrence of said data signals in relation to the availability of said storage locations, said output switching means comprising means for comparing the number of input timing pulses with the number of output timing pulses and for providing an output varying in accordance with the difference between said number of input timing pulses and said number of output timing pulses.

4. A circuit arrangement for transferring data signals from a data input source to a series of sequentially available storage locations of main data storage means, said main data storage means including a magnetic drum having a data track formed by said storage locations and a timing track having timing signals synchronized with said storage locations recorded therein, said circuit arrangement comprising, in combination, input timing pulse generating means for generating input timing pulses synchronized with the data signals of said data input source; output timing pulse generating means for generating output timing pulses from timing signals sensed from said magnetic drum; intermediate data storage means having a plurality of settable data signal storage positions; input transmitting means for transmitting data signals from said data input source to said intermediate data storage means and for recording transmitted data signals in the said intermediate data storage means; input switching means connected in said input transmitting means and controlled by both input and output timing pulses for selecting which storage position of said intermediate data storage means is to be set in accordance with each data signal of said data input source; output transmitting means for transmitting data signals from said intermediate data storage means to said main data storage means and for recording transmitted data signals in successive storage locations of the said main data storage means; output switching means connected in said output transmitting means and controlled by both input and output timing pulses for selecting a storage location of said main data storage means in which a data signal stored in said intermediate data storage means is to be stored in accordance with the difference between the number of input timing pulses and the number of output timing pulses so that data signals of said data input source are stored in successive storage locations of said main data storage means independently of variation within predetermined limits of the time of occurrence of said data signals in relation to the availability of said storage locations, said output switching means comprising means for comparing the number of input timing pulses with the number of output timing pulses and for providing an output varying in accordance with the difference between said number of input timing pulses and said number of output timing pulses.

5. A circuit arrangement for transferring data signals from a data input source including a magnetic tape having data signals recorded thereon and from which said data signals are sensed serially to a series of sequentially available storage locations of main data storage means, said

main data storage means including a magnetic drum having a data track formed by said storage locations and a timing track having timing signals synchronized with said storage locations recorded therein, said circuit arrangement comprising, in combination, input timing pulse generating means for generating input timing pulses from data signals sensed from said magnetic tape; output timing pulse generating means for generating output timing pulses from timing signals sensed from said magnetic drum; intermediate data storage means having a plurality of settable data signal storage positions, said intermediate data storage means comprising a shift register having a plurality of stages, each of said stages comprising a settable data signal storage position and each stage having an input; input transmitting means for transmitting data signals from said data input source to said intermediate data storage means and for recording transmitted data signals in the said intermediate data storage means; input switching means connected in said input transmitting means and controlled by both input and output timing pulses for selecting which storage position of said intermediate data storage means is to be set in accordance with each data signal of said data input source, said input switching means including a plurality of gates, each of said gates being adapted to be controlled to one of an open and closed condition and each of said gates being connected to a corresponding one of said shift register stage inputs, and means for controlling the condition of said gates in accordance with said input and output timing pulses, said input transmitting means being connected to transmit data signals from said data input source to the inputs of the stages of said shift register through said gates; output transmitting means for transmitting data signals from said intermediate data storage means to said main data storage means and for recording transmitted data signals in successive storage locations of the said main data storage means; output switching means connected in said output transmitting means and controlled by both input and output timing pulses for selecting a storage location of said main data storage means in which a data signal stored in said intermediate data storage means is to be stored in accordance with the difference between the number of input timing pulses and the number of output timing pulses so that data signals of said data input source are stored in successive storage locations of said main data storage means independently of variation within predetermined limits of the time of occurrence of said data signals in relation to the availability of said storage locations, said output switching means comprising means for comparing the number of input timing pulses with the number of output timing pulses and for providing an output varying in accordance with the difference between said number of input timing pulses and said number of output timing pulses.

6. A circuit arrangement for transferring data signals from a data input source including a magnetic tape having data signals recorded thereon and from which said data signals are sensed serially to a series of sequentially available storage locations of main data storage means, said main data storage means including a magnetic drum having a data track formed by said storage locations and a timing track having timing signals synchronized with said storage locations recorded therein, said circuit arrangement comprising, in combination, input timing pulse generating means for generating input timing pulses from data signals sensed from said magnetic tape; output timing pulse generating means for generating output timing pulses from timing signals sensed from said magnetic drum; intermediate data storage means having a plurality of settable data signal storage positions, said intermediate data storage means comprising a shift register having a plurality of stages, each of said stages comprising a settable data signal storage position and each stage having an input; input transmitting means for transmitting data signals from said data input source to said intermediate data

storage means and for recording transmitted data signals in the said intermediate data storage means; input switching means connected in said input transmitting means and controlled by both input and output timing pulses for selecting which storage position of said intermediate data storage means is to be set in accordance with each data signal of said data input source, said input switching means comprising a plurality of gates, each of said gates being adapted to be controlled to one of an open and closed condition and each of said gates being connected to a corresponding one of said shift register stage inputs, ring counter means adapted to be operated additively by one of said input and output timing pulses and adapted to be operated subtractively by the other of the said input and output timing pulses, said ring counter means having a plurality of stages, each of said ring counter stages being connected to a corresponding one of said gates in a manner whereby each of the said ring counter stages controls the condition of its corresponding gate, and input connecting means for applying said input and output timing pulses to said ring counter means in a manner whereby the difference between the number of the said input timing pulses and the number of the said output timing pulses controls the condition of said gates, said input transmitting means being connected to transmit data signals from said data input source to the inputs of the stages of said shift register through said gates; output transmitting means for transmitting data signals from said intermediate data storage means to said main data storage means and for recording transmitted data signals in successive storage locations of the said main data storage means; output switching means connected in said output transmitting means and controlled by both input and output timing pulses for selecting a storage location of said main data storage means in which a data signal stored in said intermediate data storage means is to be stored in accordance with the difference between the number of input timing pulses and the number of output timing pulses so that data signals of said data input source are stored in successive storage locations of said main data storage means independently of variation within predetermined limits of the time of occurrence of said data signals in relation to the availability of said storage locations, said output switching means comprising means for comparing the number of input timing pulses with the number of output timing pulses and for providing an output varying in accordance with the difference between said number of input timing pulses and said number of output timing pulses.

7. A circuit arrangement for transferring data signals from a data input source including a magnetic tape having data signals recorded thereon and from which said data signals are sensed serially to a series of sequentially available storage locations of main data storage means, said main data storage means including a magnetic drum having a data track formed by said storage locations and a timing track having timing signals synchronized with said storage locations recorded therein, said circuit arrangement comprising, in combination, input timing pulse generating means for generating input timing pulses from data signals sensed from said magnetic tape; output timing pulse generating means for generating output timing pulses from timing signals sensed from said magnetic drum; intermediate data storage means having a plurality of settable data signal storage positions, said intermediate data storage means comprising a shift register having a plurality of stages, each of said stages comprising a settable data signal storage position and each stage having an input; input transmitting means for transmitting data signals from said data input source to said intermediate data storage means and for recording transmitted data signals in the said intermediate data storage means; input switching means connected in said input transmitting means and controlled by both input and output timing pulses for selecting which storage position of said intermediate data storage means is to be set in accordance with each data signal of said data input source.

signal of said data input source, said input switching means comprising a first plurality of gates, each of said first plurality of gates being adapted to be controlled to one of an open and closed condition and each of the said gates being connected to a corresponding one of said shift register stage inputs, first ring counter means adapted to be operated additively by one of said input and output timing pulses and adapted to be operated subtractively by the other of the said input and output timing pulses, said first ring counter means having a plurality of stages, each of said first ring counter stages being connected to a corresponding one of said first plurality of gates in a manner whereby each of the said first ring counter stages controls the condition of its corresponding gate, and input connecting means for applying said input and output timing pulses to said first ring counter means in a manner whereby the difference between the number of the said input timing pulses and the number of the said output timing pulses controls the condition of said first plurality of gates, said input transmitting means being connected to transmit data signals from said data input source to the inputs of the stages of said shift register through said first plurality of gates; output transmitting means for transmitting data signals from said intermediate data storage means to said main data storage means and for recording transmitted data signals in successive storage locations of the said main data storage means; output switching means connected in said output transmitting means and controlled by both input and output timing pulses for selecting a storage location of said main data storage means in which a data signal stored in said intermediate data storage means is to be stored in accordance with the difference between the number of input timing pulses and the number of output timing pulses so that data signals of said data input source are stored in successive storage locations of said main data storage means independently of variation within predetermined limits of the time of occurrence of said data signals in relation to the availability of said storage locations, said output switching means comprising a second plurality of gates, each of said second plurality of gates being adapted to be controlled to one of an open and closed condition and each of the said gates being connected to said main data storage means, second ring counter means adapted to be operated additively and subtractively by carry pulses produced by said first ring counter means, said second ring counter means having a plurality of stages, each of said second ring counter stages being connected to a corresponding one of said second plurality of gates in a manner whereby each of the said second ring counter stages controls the condition of its corresponding gate, and output connecting means for applying carry pulses produced by said first ring counter means to said second ring counter means in a manner whereby the said second ring counter means adds and subtracts said carry pulses so that the difference between the number of input timing pulses and the number of output timing pulses controls the condition of said second plurality of gates, said output transmitting means being connected to transmit data signals from said shift register to said main data storage means through said second plurality of gates.

8. A circuit arrangement for transferring data signals from a data input source including a magnetic tape having data signals recorded thereon and from which said data signals are sensed serially to a series of sequentially available storage locations of main data storage means, said main data storage means including a magnetic drum having a data track formed by said storage locations and a timing track having timing signals synchronized with said storage locations recorded therein, said circuit arrangement comprising, in combination, input timing pulse generating means for generating input timing pulses synchronized with data signals recorded on said magnetic tape; output timing pulse generating means for generating output timing pulses from timing signals sensed from

said magnetic drum; intermediate data storage means having a plurality of settable data signal storage positions, said intermediate data storage means comprising a shift register having a plurality of stages, each of said stages comprising a settable data signal storage position and each stage having an input; input transmitting means for transmitting data signals from said data input source to said intermediate data storage means and for recording transmitted data signals in the said intermediate data storage means, said input transmitting means including time delay means; input switching means connected in said input transmitting means and controlled by both input and output timing pulses for selecting which storage position of said intermediate data storage means is to be set in accordance with each data signal of said data input source, said input switching means comprising a first plurality of gates, each of said first plurality of gates being adapted to be controlled to one of an open and closed condition and each of the said gates being connected to a corresponding one of said shift register stage inputs, first ring counter means adapted to be operated additively by one of said input and output timing pulses and adapted to be operated subtractively by the other of said input and output timing pulses, said first ring counter means having a plurality of stages, each of said first ring counter stages being connected to a corresponding one of said first plurality of gates in a manner whereby each of the said first ring counter stages controls the condition of its corresponding gate, and input connecting means for applying said input and output timing pulses to said first ring counter means in a manner whereby the difference between the number of the said input timing pulses and the number of the said output timing pulses controls the condition of said first plurality of gates, said input transmitting means being connected to transmit data signals from said data input source to the stages of said shift register through said first plurality of gates through one of a first circuit including said time delay means connecting the said data input source to the said first plurality of gates and a second circuit directly connecting the said data input source to the said first plurality of gates; selecting means for selecting one of said first and second circuits in accordance with the time relationship of said input and output timing pulses; output transmitting means for transmitting data signals from said intermediate data storage means to said main data storage means in synchronism with said output timing pulses and for recording transmitted data signals in successive storage locations of the said main data storage means; output switching means connected in said output transmitting means and controlled by both input and output timing pulses for selecting a storage location of said main data storage means in which a data signal stored in said intermediate data storage means is to be stored in accordance with the difference between the number of input timing pulses and the number of output timing pulses so that data signals of said data input source are stored in successive storage locations of said main data storage means independently of variation within predetermined limits of the time of occurrence of said data signals in relation to the availability of said storage locations, said output switching means comprising a second plurality of gates, each of said second plurality of gates being adapted to be controlled to one of an open and closed condition and each of the said gates being connected to said main data storage means, second ring counter means adapted to be operated additively and subtractively by carry pulses produced by said first ring counter means, said second ring counter means having a plurality of stages, each of said second ring counter stages being connected to a corresponding one of said second plurality of gates in a manner whereby each of the said second ring counter stages controls the condition of its corresponding gate, and output connecting means for applying carry pulses produced by said first ring counter means to said second ring counter means in a manner whereby the said second ring counter means adds and subtracts said carry pulses so that the difference between the number of input timing pulses and the number of output timing pulses controls the condition of said second plurality of gates, said output transmitting means being connected to transmit data signals from said shift register to said main data storage means through said second plurality of gates.

a manner whereby the said second ring counter means adds and subtracts said carry pulses so that the difference between the number of input timing pulses and the number of output timing pulses controls the condition of said second plurality of gates, said output transmitting means being connected to transmit data signals from said shift register to said main data storage means through said second plurality of gates.

9. A circuit arrangement for transferring data signals from a data input source to a series of sequentially available storage locations of main data storage means comprising, in combination, main data storage means including a magnetic drum having a data track formed by said storage locations, a timing track having timing signals synchronized with said storage locations recorded therein and a start track having start signals indicating a start of revolution of said magnetic drum; input timing pulse generating means for generating input timing pulses synchronized with the data signals of said data input source; output timing pulse generating means for generating output timing pulses from timing signals sensed from said magnetic drum; intermediate data storage means having a plurality of settable data signal storage positions; input transmitting means for transmitting data signals from said data input source to said intermediate data storage means and for recording transmitted data signals in the said intermediate data storage means; input switching means connected in said input transmitting means and controlled by both input and output timing pulses for selecting which storage position of said intermediate data storage means is to be set in accordance with each data signal of said data input source; output transmitting means for transmitting data signals from said intermediate data storage means to said main data storage means and for recording transmitted data signals in successive storage locations of the said main data storage means; output switching means connected in said output transmitting means and controlled by a start signal from said start track for selecting a storage location of the data track of said main data storage means in which a data signal stored in said intermediate data storage means is to be stored so that data signals of said data input source are stored in predetermined storage locations of said main data storage means independently of variation within predetermined limits of the time of occurrence of said data signals in relation to the availability of said storage locations, said output switching means comprising means for deriving start signals from said start track and selecting means for selecting a storage location of the data track of said main data storage means in accordance with a start signal derived from the said start track.

10. A circuit arrangement for transferring data signals from a data input source to a series of sequentially available storage locations of main data storage means comprising, in combination, main data storage means including a magnetic drum having a data track formed by said storage locations, a timing track having timing signals synchronized with said storage locations recorded therein and a start track having start signals indicating a start of revolution of said magnetic drum; input timing pulse generating means for generating input timing pulses synchronized with the data signals of said data input source; output timing pulse generating means for generating output timing pulses from timing signals sensed from said magnetic drum; intermediate data storage means having a plurality of settable data signal storage positions, said intermediate data storage means comprising a plurality of shift registers each having a plurality of data storage positions, each of said shift registers having a pair of inputs; input transmitting means for transmitting data signals from said data input source to said intermediate data storage means and for recording transmitted data signals in the said intermediate data storage means; input switching means connected in said input transmitting means and controlled by both input and output timing

pulses for selecting which storage position of said intermediate data storage means is to be set in accordance with each data signal of said data input source, said input switching means including a first plurality of gates, each 5 of said first plurality of gates being adapted to be controlled to one of an open and closed condition and each of the said gates being connected to an input of a corresponding one of said shift registers, said input transmitting means being connected to transmit data signals from said data input source to one of the inputs of said shift registers through said first plurality of gates so that the said first plurality of gates controls the selective transmission of data signals to the said shift registers, a second plurality of gates, each of said second plurality of gates 10 being adapted to be controlled to one of an open and closed condition and each of the said gates being connected to the other input of a corresponding one of said shift registers, said input transmitting means being connected to transmit input timing pulses from said input timing pulse generating means to the other of the inputs of said shift registers through said second plurality of gates in a manner whereby the said second plurality of gates controls the selective transmission of input timing pulses to the said shift registers, said input timing pulses 15 controlling the said shift registers as shifting pulses, and input control means for controlling the condition of said first and second plurality of gates; output transmitting means for transmitting data signals from said intermediate data storage means to said main data storage means and for recording transmitted data signals in successive storage locations of the said main data storage means; output switching means connected in said output transmitting means and controlled by a start signal from said start track for selecting a storage location of the data track 20 of said main data storage means in which a data signal stored in said intermediate data storage means is to be stored so that data signals of said data input source are stored in predetermined storage locations of said main data storage means independently of variation within predetermined limits of the time of occurrence of said data signals in relation to the availability of said storage locations, said output switching means comprising means for deriving start signals from said start track and selecting 25 means for selecting a storage location of the data track of said main data storage means in accordance with a start signal derived from the said start track.

11. A circuit arrangement for transferring data signals from a data input source to a series of sequentially available storage locations of main data storage means comprising, in combination, main data storage means including a magnetic drum having a data track formed by said storage locations, a timing track having timing signals synchronized with said storage locations recorded therein and a start track having start signals indicating a start of revolution of said magnetic drum; input timing pulse generating means for generating input timing pulses synchronized with the data signals of said data input source; output timing pulse generating means for generating output timing pulses from timing signals sensed from said magnetic drum; intermediate data storage means having a plurality of settable data signal storage positions, said intermediate data storage means comprising a plurality of shift registers each having a plurality of data storage positions, each of said shift registers having a pair of inputs; input transmitting means for transmitting data signals from said data input source to said intermediate data storage means and for recording transmitted data signals in the said intermediate data storage means; input switching means connected in said input transmitting means and controlled by both input and output timing pulses for selecting which storage position of said intermediate data storage means is to be set in accordance with each data signal of said data input source, said input switching means including a first plurality of gates, each of said first plurality of gates being adapted 30

to be controlled to one of an open and closed condition and each of the said gates being connected to an input of a corresponding one of said shift registers, said input transmitting means being connected to transmit data signals from said data input source to one of the inputs of said shift registers through said first plurality of gates so that the said first plurality of gates controls the selective transmission of data signals to the said shift registers, a second plurality of gates, each of said second plurality of gates being adapted to be controlled to one of an open and closed condition and each of the said gates being connected to the other input of a corresponding one of said shift registers, said input transmitting means being connected to transmit input timing pulses from said input timing pulse generating means to the other of the inputs of said shift registers through said second plurality of gates in a manner whereby the said second plurality of gates controls the selective transmission of input timing pulses to the said shift registers, said input timing pulses controlling the said shift registers as first shifting pulses, first control means for controlling the condition of said first and second plurality of gates, a third plurality of gates, each of said third plurality of gates being adapted to be controlled to one of an open and closed condition and each of the said gates being connected to said other input of a corresponding one of said shift registers, connecting means for transmitting output timing pulses from said output timing pulse generating means to said other of the inputs of said shift registers through said third plurality of gates in a manner whereby the said third plurality of gates controls the selective transmission of output timing pulses to the said shift registers, said output timing pulses controlling the said shift registers as second shifting pulses, and second control means for controlling

the condition of said third plurality of gates, said second control means including counter means adapted to control the condition of said third plurality of gates in a manner whereby the said third plurality of gates controls the selective transmission of output timing pulses to the said shift registers and counter control means for applying said input timing pulses and said start signals to said counter means in a manner whereby the said input timing pulses and the said start signals control the condition of said third plurality of gates; output transmitting means for transmitting data signals from said intermediate data storage means to said main data storage means and for recording transmitted data signals in successive storage locations of the said main data storage means; output switching means connected in said output transmitting means and controlled by a start signal from said start track for selecting a storage location of the data track of said main data storage means in which a data signal stored in said intermediate data storage means is to be stored so that data signals of said data input source are stored in predetermined storage locations of said main data storage means independently of variation within predetermined limits of the time of occurrence of said data signals in relation to the availability of said storage locations, said output switching means comprising means for deriving start signals from said start track and selecting means for selecting a storage location of the data track of said main data storage means in accordance with a start signal derived from the said start track.
